Specification for Design.

Patented May 24, 1921.

Application filed January 10, 1921. Serial No. 436,377. Term of patent 14 years.

To all whom it may concern:

Be it known that we, EDWARD G. ALLEN and ABNER A. HAGAR, citizens of the United States of America, residing in the city of Seattle, in the county of King, in the State of Washington, have invented a new and original ornamental Design for a Casing for Scales, of which the following is a specification, reference being had to the accompanying drawing, forming part thereof.

The figure is a perspective view of a casing for scales showing our new design.

We claim:

The ornamental design for casing for scales as shown.

In testimony whereof, we have hereunto set our hands in the presence of two subscribing witnesses.

EDWARD G. ALLEN.
ABNER A. HAGAR.
